Primary Examiner — Cathron Brooks*Assistant Examiner* — Sharon S Oum(74) *Attorney, Agent, or Firm* — Finnegan, Henderson, Farabow, Garrett & Dunner, LLP(57) **CLAIM**

The ornamental design for a portion of a display screen with icon, as shown and described.

DESCRIPTION

The FIGURE is a front view of a portion of a display screen with icon showing the new design.

The broken lines illustrate a portion of the display screen and form no part of the claimed design.
